UNITED STATES PATENT OFFICE.

JAMES A. WILSON, OF FULDA, MINNESOTA.

FOLDING GLASS WINDOW.

1,262,892.

Specification of Letters Patent. Patented Apr. 16, 1918.

Application filed March 9, 1917. Serial No. 153,633.

To all whom it may concern:

Be it known that I, JAMES A. WILSON, a citizen of the United States, residing at Fulda, in the county of Murray and State of Minnesota, have invented a new and useful 5 Folding Glass Window, of which the following is a specification.

The present invention has for its object the provision of a folding glass window of 10 novel and improved construction, adapted for use upon the side curtains of automobile tops, although useful for various other purposes.

It is the object of the invention to provide 15 a novel assemblage of the component elements constituting the window, whereby the window will be wind and rain proof, and can be folded, the construction being simple and inexpensive.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

30 The invention is illustrated in the accompanying drawing, wherein:—

Figure 1 is a face view of the improved window, portions being broken away.

Figs. 2 and 3 are enlarged sectional details taken on the respective lines 2—2 and 3—3 of Fig. 1.

Fig. 4 is an enlarged fragmental plan view of one of the sheets attached to the ends of the sashes.

40 Fig. 5 is a similar view of one of the sheets which are between the sashes.

Fig. 6 is a perspective view of one corner of one sash showing the members thereof detached.

45 Fig. 7 is a face view of a modified form of window.

Fig. 8 is an enlarged sectional detail taken on the line 8—8 of Fig. 7.

The window embodies a series of parallel 50 panels 1 of glass or other transparent material, which are elongated and arranged vertically, although they can be disposed in various positions. Each panel has its margin fitted within a rectangular sash comprising the longitudinal side members 2 and the end members 3, said members being of U-

shaped section so as to straddle the edges and ends of the panel, and the ends of the members 2 and 3 are preferably beveled, and can be soldered or otherwise secured together, after the parts are assembled.

Upper and lower sheets 4 are applied to the ends of the sashes and panels, and opposite sheets 5 are applied to the free portions of the remote sashes, while sheets 6 are applied to the adjacent portions of the sashes to close the spaces therebetween and to hingedly connect them. These sheets or pieces of fabric are composed of rubberized fabric or any other suitable wind and water proof material, or any other suitable pliant material.

Each sheet 4 is of elongated form to extend across the ends of the sashes and panels, and is provided with a series of openings 7, 75 which as illustrated are of hexagonal form, while the ends of the sheet 4 has V-shaped recesses. Said openings and recesses provide webs 7', one for each sash, and the sheet 4 has a longitudinal fold line 8 along its median portion, and has a pair of longitudinal fold lines 8' at the opposite sides of and parallel with the intermediate fold line 8, these fold lines being in the webs 7'. The webs 7' are doubled and tucked within the end members 3 of the sashes, as seen in Fig. 3. Thus, each web 7' is doubled or folded on the fold line 8 to fit within the sash member 3 around the end of the corresponding panel 1 and the web is folded back away 90 from the panel on the fold lines 8' around the edges of the sash member 3. Those portions of the webs between the fold lines 8 and 8' are doubled and fitted within the sash members on the end portions of the panels, 95 and the sheet 4 is provided with notches 9 in the fold lines 8', where the webs turn over the edges of the sash member. The edge portions or halves 10 of the sheet 4 are folded against each other and are connected by a 100 line of stitching 11 extending longitudinally of the sheet near the intermediate folded portion of the sheet, thus holding the sheet in doubled form. The sheets 5 are similar in construction to the sheets 4, but do not 105 have the openings 7, which are necessary to provide the individual webs 7' for the ends of the sashes. The sheets 5 have their intermediate longitudinal portions folded on the fold lines 8 and 8', the same as the sheets 4, 110 to fit within and around the members 2 which are farthest remote from one another.

The sheets 5 have lines of stitches 11 for holding the edge portions or halves 10 thereof together and the ends of the sheets 4 and 5 can be overlapped and fastened together 5 in any suitable manner, if desired.

The sheets 6 are of elongated rectangular form, and each of them is provided adjacent to each of its ends with transversely spaced openings 12, which as illustrated, are of 10 diamond shaped form, thereby providing longitudinally elongated webs 13 between the openings at the opposite ends. The webs have longitudinal intermediate fold lines 14, and longitudinal fold lines 15 at 15 opposite sides of and parallel with the respective fold lines 14, whereby the webs can be doubled and folded to fit within the adjacent sash members 2, the same as the webs of the sheets 4 and 5 fit in their respective 20 sash members. There are notches 16 in the sheet 6 at the ends of the fold lines 15 adjacent to the openings 12, whereby the sheet can be folded back around the edges of the sash members 2, and the sheet 6 has a 25 longitudinal portion 17 between the webs 13 which is preferably disposed at the outer side of the window between the respective panels 1. The edge portions 18 of the sheet 6 at the opposite sides are folded back and 30 overlap each other at the inner side of the window, as seen in Fig. 2. The sheet 6 has slits 19' extending from its ends to the openings 12, thereby providing the flaps 19 at the ends of the portions 17 and the flaps 20 35 at the ends of the edge portion 18. The webs 13 are folded and doubled to fit within the adjacent sash members 2 over the side edges of the corresponding panels, with the portions 17 at outside between the sash 40 members, and the edge portions 18 are folded back and overlapped including their flaps 20. A line of stitches 21 extending longitudinally along the median line of the portion 17 serves to secure the overlapped edge 45 portions 18 to the portions 17, and the flaps 19 and 20 are also held to the sheets 4 by the lines of stitches 11 thereof. The flaps 19 and 20 close the openings 7 of the sheets 4, and the sheets 6 provide hinge connections 50 between the sashes, thereby enabling the sashes to be folded together on the lines of stitches 21 as fold lines. The sheets 6 close the spaces between the sashes, and it will be noted that all of the sheets are of two layer 55 or two ply construction when the window is completed, and all of the sheets have the re-entrant folds fitting with the sash members over the edges and ends of the panels, thereby providing packing between the sashes 60 and panels to render the window wind and rain proof, and to avoid the chipping or breaking of the panels, since they are fitted within the re-entrant folded portions of the sheets which are in turn fitted within the 65 sashes. The sheets 4 and 5 can be sewed or

otherwise fastened to the curtain or other member to which the window is to be applied. The metallic sash members 2 and 3 are entirely inclosed by the fabric sheets, and the window is practically indestructible 70 and is also ornate in appearance.

In the modified form, two sheets or layers 4' are employed, the same being provided with openings for the panels 1, and the sheets 4' have lips 4^a surrounding their 75 openings and folded back and tucked within the members of the sashes 2, whereby the lips 4^a are disposed between the margins of the panels and the sashes. With this form, only two sheets are necessary, one upon the 80 outside and the other upon the inside of the window.

Having thus described the invention, what is claimed as new is:—

1. A window of the character described 85 embodying a sash, a panel therein, and doubled sheets having their folded portions fitting between the sash and panel and portions secured together outside of the sash.

2. A window of the character described 90 embodying a sash, a panel therein, and doubled sheets having re-entrant folds fitting within the sash members upon the edge portions of the panel, the portions of the sheets being secured together around the 95 sash.

3. A window of the character described 100 embodying a sash, a panel therein, said sash having members receiving edge portions of the panels, and sheets extending entirely around the sash members and having portions fitted between the sash members and panel, the sheets being secured together around the sash.

4. A window of the character described 105 embodying a pair of sashes, a panel fitting in each sash, and a sheet between the sashes having intermediate and edge portions, and re-entrant folded portions between said intermediate and edge portions fitted within 110 the adjacent sashes upon the edges of the panels, said edge portions being secured to the intermediate portions.

5. A window of the character described 115 embodying a plurality of sashes, a panel fitted in each sash, and a sheet having openings providing webs, one for each sash, said webs being doubled and provided with re-entrant folds fitted within the respective sashes upon the panels.

6. A window of the character described 120 embodying a plurality of sashes, a panel within each sash, a sheet having webs fitted between the ends of the panels and corresponding sash members, and a sheet between each pair of adjacent sash members having portions fitted between said sash members and panels and having a portion secured to the aforesaid sheet.

7. A window of the character described 130

embodying a plurality of sashes, a panel fitted within each sash, sheets having openings providing webs, said webs having doubled folds fitted within the ends of the 5 sashes upon the ends of the panels, and a sheet between each pair of sashes having doubled folds fitted within the adjacent sash members upon the edges of the panels, the ends of the last mentioned sheet 10 being secured to the aforesaid sheets between the webs thereof.

8. A window of the character described embodying a series of parallel sashes, a panel fitted within each sash, doubled sheets 15 having openings providing webs, said webs being doubled and having reentrant folds fitted within the ends of the sashes upon the ends of the panels, and a sheet between each pair of sashes having intermediate and edge

portions, and webs between said intermediate and edge portions, the last mentioned webs being doubled and provided with reentrant folds fitted within the adjacent sash members upon the edges of the panels, the edge portions of the last mentioned sheet being secured to the intermediate portion thereof, and the ends of said intermediate and edge portions having flaps secured to the aforesaid sheets over the 20 openings thereof.

In testimony that I claim the foregoing as my own, I have hereto affixed my signature in the presence of two witnesses.

JAMES A. WILSON.
